CLAIM

The ornamental design for a wireless communication module, as shown and described.

DESCRIPTION

The file of this patent contains at least one drawing/photograph executed in color. Copies of this patent with color drawing(s)/photograph(s) will be provided by the Office upon request and payment of the necessary fee.

1. Wireless communication module

2. Wireless communication module

1.1 : Perspective

1.2 : Front

1.3 : Back

1.4 : Right

1.5 : Left

1.6 : Top

1.7 : Bottom

2.1 : Perspective

2.2 : Front

2.3 : Back

2.4 : Right

2.5 : Left

2.6 : Top

2.7 : Bottom

The broken lines do not form a part of the claimed designs; the grey colored portion in reproductions No. 2.1 to 2.7 do not form a part of the claimed designs; the white colored portion in reproductions No. 2.1 to 2.7 indicate reflective highlights on the surface of the product and do not form a part of the claimed designs.
